UNITED STATES PATENT OFFICE.

WINFIELD HANCOCK YOST, OF MONTREAL, QUEBEC, CANADA, ASSIGNOR TO RODGER
BALLAST CAR COMPANY, OF CHICAGO, ILLINOIS, A CORPORATION OF MAINE.

CAR.

1,053,118.

Specification of Letters Patent. Patented Feb. 11, 1913.

Original application filed July 6, 1908, Serial No. 442,106. Divided and this application filed October 12, 1911. Serial No. 654,343.

To all whom it may concern:

Be it known that I, WINFIELD H. YOST, a citizen of the United States, residing at Montreal, in the Province of Quebec, 5 Dominion of Canada, have invented certain new and useful Improvements in Cars, of which the following is a specification.

This invention relates to an improved side stake for railway cars.

10 This invention is a division of the matter originally shown and claimed in my application Serial No. 442,106, filed July 6, 1908.

In the drawings—Figure 1 shows a transverse section of a car embodying my invention. Fig. 2 is a side elevation of the improved stake construction. Fig. 3 is a view partly in section on the line 3 3 of Fig. 2. Fig. 4 is a section on the line 4 4 of Fig. 1. Fig. 5 is 20 a sectional view on the line 5 5 of Fig. 2.

Like reference numerals refer to like elements throughout the drawings, in which I have illustrated my invention in connection with a convertible center dump hopper car although, as will be apparent, my improved side stakes are applicable to cars of other types. The sides of the car illustrated are formed of doors, 1, hinged at their upper edges to the top rail, 2, the latter being supported upon the side stakes 3. The floor of the car comprises stationary horizontal side sections, 4, extending from the intermediate sills 5 to the side sills 6. Hinged longitudinally of the car over the intermediate 30 sills 5 are central floor sections, 7, adjustable either to the position shown at the left of Fig. 1 or to the position shown at the right of that view. Adjustment to former position forms a flat bottom gondola car and adjustment to the latter position forms a center dump hopper car. The central longitudinal hopper comprises a stationary inclined side 40 8 and an opposed side consisting of a door, 9, hinged at 10 to the intermediate sill 5.

45 As my invention is applicable to many types of car the foregoing brief description of the particular car illustrated is sufficient for the purposes of this application.

My improved side stake 3 is preferably 50 composed of a channel iron 11 and an angle bar 12 having their webs adjacent and secured together as shown in Fig. 4. These parts are preferably secured together in such

manner that the flange 13 of the angle iron and the flange 14 of the channel iron extend 55 in opposite directions in the same plane. Adjacent the lower extremity of the parts 11 and 12 and secured therebetween is a metal plate 15 which projects beneath the members 11 and 12 and has secured to its 60 projecting part an angle iron 16. A transverse gusset plate 17 is secured to and extends between the side sill 6 and intermediate sill 5 and to this gusset plate 17 the inner end of the angle iron 16 is riveted. 65 The gusset plate 18 overlies and is secured to the upper sides of the intermediate and side sills and a brace 19 is secured between the members 11 and 12 of the side stake and projects inwardly above the gusset plate 18. 70 The brace 19 is provided with a horizontal flange 20 which is secured to the gusset plate 18. By the construction described the side stake is firmly anchored at two points well spaced apart, and is thus well calculated to 75 resist the stresses imposed upon it in service.

Secured to the vertical portion of the plate 19 and on the opposite side from the horizontal flange 20 is a small angle iron 21 secured to the brace 19 and to the plate 18. 80 At the upper extremity of the stake 3 and having one flange secured between the members 11 and 12 is a small angle iron 22 having a horizontally directed flange 22' to which is adapted to be secured the top rail 85 2 of the car, shown in this instance as formed of a longitudinally extending I-beam 23 carrying a wooden or other strip 24 at its upper portion. Where it is intended to use this type of stake in a car designed for unloading by means of a plow, I preferably provide my stake 20 with a reinforcing and protecting member 25 having flanges 26, as shown in Fig. 5 of the drawings. 90 95

What I desire to protect by United States Patent and claim is—

1. In a car, an underframe, a side sill forming part of said underframe, a side stake on the outer side of said underframe 100 and extending upwardly therefrom, braces secured to said side stake and extending inwardly therefrom above and below said side sill and secured to said underframe.

2. In a car, a side stake, a side sill, an intermediate sill, and braces secured to said 105

side stake and extending above and below said side sill and secured to said intermediate sill.

3. In a car, a side stake comprising an angle iron and a channel beam having their webs riveted together.

4. In a car, a side stake comprising an angle iron and a channel beam, said angle iron having one side secured to the web of said channel beam in such a manner that the free side of said angle iron and one of the flanges of said channel beam will extend in opposite directions.

5. In a car, a side stake comprising an angle iron and a channel beam, said angle iron having one side secured to the web of said channel beam in such a manner that the free side of said angle iron and of the flanges of said channel beam will extend

in opposite directions and lie approximately 20 in the same plane.

6. In a car, a side stake comprising an angle iron and a channel beam, said angle iron having one side secured to the web of the channel beam in such a manner that the free side of said angle iron and one of the flanges of said channel beam will extend in opposite directions and lie in approximately the same plane, and a reinforcing member secured to the oppositely extending flange 30 and side of said channel beam and angle bar, respectively.

In testimony whereof, I have subscribed my name.

WINFIELD HANCOCK YOST.
